UNITED STATES PATENT OFFICE.

HENRY J. LUTCHER, OF ORANGE, TEXAS.

TEMPERATURE-REGULATOR.

SPECIFICATION forming part of Letters Patent No. 396,215, dated January 15, 1889.

Application filed July 20, 1888. Serial No. 280,581. (No model.)

To all whom it may concern:

Be it known that I, HENRY J. LUTCHER, a citizen of the United States, residing at Orange, in the county of Orange and State of Texas, have invented a new and useful Improvement in Temperature-Regulators, of which the following is a specification.

My invention relates to improvements in thermostatic devices for automatically regulating the temperature of lumber-driers; and it consists in certain novel features hereinafter described and claimed.

In the annexed drawings, which fully illustrate my invention, Figure 1 is a side elevation of my improved device as applied to a lumber-drier, the latter being shown in section. Fig. 2 is a vertical section on the line *xx* of Fig. 1. Fig. 3 is a side view of a modification, and Fig. 4 is a section on line *yy* of Fig. 3.

Referring to the drawings by letter, A designates a lumber-drier of the usual construction, in the lower side of which is a furnace, B, having at its front end a vertically-movable draft-regulating door, C. In the top of the dries are a pair of doors, D, which are hinged at their lower sides and are adapted to close or uncover an opening, E, in the roof.

F represents a vertical bracket, which projects from the roof and is provided with a guiding-sheave, G.

H represents a hollow tube or thermal bar, which is made of iron, brass, or any other expandable metal, the said tube being rigidly secured at its inner end to one side of the drier, as at I, and said tube passes through a guide, K, in the opposite side of the drier and projects beyond the same, as shown. That portion of the tube which is arranged within the drier is provided with a number of perforations, J, by means of which caloric currents may pass into the tube, as well as circulate around the same, so as to cause the tube to become thoroughly heated and expanded to a maximum extent. At a suitable distance from one side of the drier is erected a frame, K', to which is secured a quadrant arm, L, the same being provided at its perimeter with a scale, M, which is graded up to any desired point.

N represents a lever-arm which is ful-

crumed to the quadrant at the lower corner thereof, and is provided at its upper end with a pointer, O, moving in front of the scale M. The outer end of the hollow tube or thermal bar is pivoted to the lever-arm N, near and below the fulcrum of the same, as shown at P, and the said arm is thereby adapted to be operated by the said tube as it expands and contracts by the action of the heat. From one side of the arm N projects an ear or lug, Q, which has a plain transverse opening.

R represents a horizontal tappet-arm, which has one end provided with screw-threads and slipped through the openings in the ear or lug Q, the opposite end of said arm being turned downward and provided with a slotted eye, S.

T represents a pair of clamping-nuts, which are screwed on the threaded portion of the arm R and bear against the opposite sides of the ear or lug Q. These nuts secure the arm firmly to the said lug, and by turning the said nuts the arm may be adjusted longitudinally, as will be readily understood.

The frame K' is provided at one of its upper corners with a vertical beam or arm, U, to the upper end of which is secured a sleeve, V.

W represents a rod, which has one end passed through the sleeve V and provided with clamping-nuts X, which engage screw-threads on the said rod and bear against opposite sides of the sleeve, thereby securing said rod firmly in said sleeve and permitting it to be adjusted in a longitudinal direction. The opposite end of the said rod is normally passed through the eye S of the arm R.

Y designates a guiding-sheave, which is journaled on a suitable support, Z, and arranged about on a level with the sheave G.

a designates a cord, which is connected to the free sides of the doors D, passes over the sheaves G Y, and is provided at its lower end with a ring, b, which is slipped over the end of the rod W and bears against the eye S of the arm R.

The sweep-arm is extended past its fulcrum, and is provided with an integral arc, c, provided with gear-teeth d, which mesh with gear-pinion e, journaled on the support Z. This pinion in turn meshes with the gear-

wheel *f*, rigidly secured on a shaft, *g*, journaled on the side of the dry-house, and this gear-wheel in turn meshes with a rack-bar, *h*, rising from the door *C*. The door *C* is further provided with a second similar rack-bar, which meshes with a second gear-wheel on the shaft.

The operation of the device is as follows: The thermal bar is caused to expand by the 10 action of the heat in the dry-house, and the lever-arm is thereby made to play over the scale of the quadrant and indicate the temperature of the drier. When the heat becomes so great as to endanger the lumber 15 therein, the tubular rod or thermal bar expands to such an extent as to sweep the lower arm over the quadrant sufficiently far to cause the doors *C* to be lowered and closed through the medium of the rack-bars, gear-wheels, and toothed sector, as will be readily 20 understood. At the same time the lever-arm carries the arm *R* inward, so as to throw the ring *b* from the rod *W*, thereby releasing the cord *a* and allowing the doors *D* to close by 25 their own gravity, thereby effectually cutting off all the draft.

It will be readily understood that under ordinary conditions the thermal bar expands and contracts under varying conditions of 30 temperature in the drier, and thereby moves the sweep arm, as before described, and operates the gearing to automatically adjust the doors to partly cut off or increase the supply of air to the furnace as may be necessary to 35 maintain the air in the drier at a uniform temperature.

In Figs. 3 and 4 I have illustrated a modification of my device. In this form of my invention I dispense with the rack-bars, the 40 gear-wheels, and the toothed sector, and instead I mount on the rock-shaft the crank-wheels *k*, one of which may be connected to the lever or sweep arm by means of a connecting-rod, *l*, as shown. On one side of the 45 crank-wheels are the projecting points *m*. *n*

designates rods or chains, which have their lower ends connected to the draft-regulating doors *C* and their upper ends provided with eyes *o*, which are slipped over the point *m*. In this form of my device, when the heat becomes very great the crank-wheels will be rotated to bring the pins *m* to such a point that the eyes will slip off them, thereby allowing the doors *C* to close by their own gravity. 50

Having thus described my invention, I 55 claim—

1. The combination of the sweep-arm, the expandable rod pivoted thereto, the vertical arm *U*, the rod *W*, adjustably supported thereon, the tappet-arm carried by the sweep-arm 60 and moving on the rod *W*, the doors *D*, and the cord extending therefrom and having a ring engaging the rod *W* and adapted to be disengaged therefrom by the tappet-arm, as set forth. 65

2. The combination of the sweep-arm, the expandable rod pivoted thereto, the door *C*, gearing between the same and the sweep-arm, the tappet-arm carried by the sweep-arm, the doors *D*, and intermediate devices whereby 70 said doors *D* are closed by the tappet-arm, substantially as set forth.

3. The combination of the sweep arm or lever, the expandable rod pivoted to said sweep-arm, the door *C*, provided with rack-bars, and 75 gearing between said rack-bars and the sweep-arm, as set forth.

4. The combination of the sweep-arm provided with an integral toothed sector, the expandable rod pivoted to the sweep-arm, the 80 door *C*, having the rack-bars, and gearing between the rack-bars and the sector, as set forth.

In testimony that I claim the foregoing as my own I have hereto affixed my signature in presence of two witnesses.

HENRY J. LUTCHER.

Witnesses:

E. W. BANCROFT,
W. A. JOHNS.
